UNITED STATES PATENT OFFICE

EDWIN S. PRIDHAM, OF OAKLAND, CALIFORNIA, ASSIGNOR TO THE MAGNAVOX COMPANY, OF OAKLAND, CALIFORNIA, A CORPORATION OF ARIZONA

LOUD SPEAKER

Application filed February 19, 1939. Serial No. 341,231.

This invention relates to loud speakers of the moving coil type, and has for its object to simplify and improve the construction and operation of such a device.

These devices include a field coil surrounding a field magnet and enclosed in a housing which forms a magnetic path leading across a narrow air gap in which a moving coil is disposed. It is essential that the moving coil be exactly centered in the air gap and that the elements of the magnetic structure forming the air gap be also exactly centered. This moving coil, in present-day practice, is mounted directly on the apex of a conical diaphragm flexibly supported at its rim by a frame which is secured to a portion of the magnet housing. Should this diaphragm, which is usually of paper, be punctured, it is advantageous to be able to substitute another diaphragm assembly without resorting to factory methods and fixtures for exactly centering the coil in the narrow air gap. In other words, it is highly desirable that a structure be provided in which interchangeability of parts is permitted, so that the diaphragm assembly of one device will fit the magnetic structure of any other device.

In addition, it has become general in the trade for a manufacturer of radio receiving sets to obtain loud speakers from some distant source, and one of the largest items of cost in the shipping of these loud speakers is the field coil or winding, which of itself weighs almost as much as the remainder of the structure. In and by the present invention, a structure is provided in which all of the elements except the field coil or winding may be shipped to the manufacturer of the receiving set, and the latter without any difficulty or without special tools or equipment, may insert the field coil and be assured that the parts when assembled will be correctly spaced and centered. Such a structure requires ready accessibility to the interior of the housing, so as to permit of insertion of the field coil, which usually requires demounting, and facility of reassembly without special tools or equipment in the way of centering devices.

In the accompanying drawings,

Fig. 1 shows a longitudinal central sec-

tional view of one form which my invention may assume;

Fig. 2 shows a plan view in section of the same, taken on the line II—II of Fig. 1;

Fig. 3 shows a longitudinal central sectional view of a slightly modified form of the invention, in which the top portion of the housing is removable; 55

Fig. 4 shows a similar view of a further modification, in which the bottom plate of 60 the housing is removable.

Fig. 5 is a view in elevation showing the spacing ring used for centering and properly locating the poles of the magnetic structure.

The device as herein shown comprises an 65 iron housing 10, usually cylindrical in form, and containing an axial field magnet 11 and a field coil 12. The field magnet is secured to one end of the housing and projects through an opening in the opposite end of the housing, which opening is slightly larger than the field magnet, so as to leave a very narrow, 70 circular air gap. The housing, for the sake of accessibility, may be parted near its middle portion as shown in Fig. 1, the two halves being secured together by bolts 13 fastened in flanges 14; or as shown in Figs. 3 and 4, one of the end walls, either the top or bottom, may be separately formed and detachably secured to the remainder of the housing by 75 suitable fasteners 15.

The field coil 12 is removably mounted in the housing, fitting freely around the field magnet 11 and being held in place by means of a nut 16 on the field magnet, as shown in 85 Fig. 1; or by other means, such as wedges 17 or other like fasteners between the coil and housing, as shown in Figs. 3 and 4.

Secured to one end wall of the housing is a diaphragm-holding frame 18 carrying a diaphragm 19 preferably in the form of a cone, on the apex of which is mounted a movable coil 20. It is essential that this coil be exactly centered within the annular air gap, and that the said gap be perfectly true. In order to insure centering of the elements forming the air gap, and a correct positioning of the coil therein, without the use of special tools when assembling the separable parts of the housing, one of which in all cases carries the 90

diaphragm assembly, including the movable coil, and the other of which carries the field magnet 11, I provide a spacing ring 21 on the inner side of the apertured end wall of 5 the magnet housing, which spacing ring is of brass or other non-magnetic material, and is formed with an opening of the exact size of the adjacent end of the field magnet 11, over which it fits snugly. This spacing ring is 10 riveted or otherwise secured in place on said end wall with the aid of a fixture which insures that when it is finally placed over the end of the field magnet 11 the projecting end of the latter will be exactly centered with 15 respect to the opening in the adjacent end wall of the magnet housing, leaving an air gap of even spacing throughout.

The rim of the conical diaphragm should be supported and restrained against blasting; 20 and this is preferably accomplished by the use of a connecting strip or band 19^a, of limp leather or the like, between the rim of the cone and the supporting frame 18. The use of such connecting bands permits of a certain freedom of movement laterally of the 25 apex of the cone and the vibrating coil carried thereby, to such an extent that additional and adjustable spacing means are required, to insure exact centering of the vibrating coil. 30 The moving coil and the apex of the cone must be flexibly supported so as to permit free movement of both in an axial line while restraining them against any lateral movement. This may be done in several ways, one 35 such consisting of a plurality of extremely thin arms 22, of light material, having a certain degree of resilience or springiness secured at their inner ends to the frame of the moving coil, and at their outer ends to a 40 ring 23. This ring 23 is held in place on the outer surface of the end wall of the housing in which the air gap is formed, by means of screws 24 passing through the spacing rings 21 and thence through large openings in said 45 end wall. When the screws are loosened, the ring 23 may be shifted about sufficiently, on account of the large openings, to bring the moving coil 20 into the exact position it should occupy in the air gap; whereupon, 50 by tightening the screws, the position of the coil becomes fixed. This operation is done in the factory, and a convenient way of carrying it out is to place the diaphragm assembly in inverted position, with a fixture correspond- 55 ing in size to the end of the field magnet 11 passing through the opening in the spacing ring 21 and into the interior of the movable coil. The said spacing ring is notched out 60 in several places as indicated at 25, so that the operator may be able to see when the coil is in correct position. The screws 24 are then tightened up, and this setting, having once been made, should remain unchanged.

As a result of this construction, the dia- 65 phragm assembly can easily and quickly be

removed from the magnetic structure by separating the elements of the housing 10. Such assembly includes one element of the housing in all cases; and so upon removal of the diaphragm assembly the interior of the 70 housing is exposed and the field coil may be inserted or removed and the parts readily put together again, merely by clamping or otherwise securing the two elements of the housing together. Even though the parts fit 75 loosely, or their former position is slightly disturbed, the setting of the air gap and the position of the moving coil therein will always be correct, owing to the spacing ring 21. As above stated, this is of great advantage in that it permits shipping of the device without the field coil, the latter being inserted at a later time when ready for final assembly; and it also permits of repairs being made 80 involving the replacement of the diaphragm or moving coil. When this occurs, the diaphragm assembly is simply removed and another assembly of the same size substituted, the spacing ring again insuring that the parts will be correctly fitted together and the moving coil accurately spaced.

Having thus described my invention, what I claim as new and desire to secure by Letters Patent is:

1. A method of constructing and assembling a loud speaker of the type employing a casing of magnetizable material, formed in endwise, separable sections, with an aperture in one end and a field magnet secured to the opposite end, the said field magnet extending through the aperture and spaced therefrom, so as to leave a narrow air gap in which is disposed a movable coil attached to a sound regenerating diaphragm, which consists of placing a spacing ring of non-magnetic material upon the apertured end wall having an opening of a size to exactly fit over the adjacent end of the field magnet, and so positioned as to bring the magnetic elements into position where the air gap is of uniform width throughout, and attaching through peripheral supporting means on the diaphragm, the said diaphragm and moving coil to the apertured end wall and centering the said moving coil with relation to the aperture in the spacing ring by employment of shiftable, lockable connections between the said moving coil and the apertured end wall, and providing said spacing ring with a plurality of notches to reveal the position of the moving coil relative to the aperture in the end wall, and a fixture inserted in the opening in the spacing ring.

2. A loud speaker comprising a casing of magnetizable material, formed with an opening in one end wall, a field magnet within the casing, fixed to the opposite end wall and projecting into said opening so as to leave an annular air gap, said casing being formed with endwise sections detachably connected

together, a field coil in the casing surrounding said field magnet, a movable coil disposed in the said air gap, a conical diaphragm secured to said coil, a flexible support for the rim of the diaphragm, secured to the adjacent end wall of the casing, a spacing ring on the apertured end wall having an opening to exactly fit the adjacent end of the field magnet and bring the two parts of the casing into position where the air gap will be of uniform width throughout, and a flexible support for the movable coil adjustably secured upon the adjacent end wall of the casing independent of said flexible support for the rim of the diaphragm, whereby the movable coil can be adjusted in the air gap independently of the diaphragm support.

3. A loud speaker comprising a casing of magnetizable material, formed with an opening in one end wall, a field magnet within the casing, fixed to the opposite end wall and projecting into said opening so as to leave an annular air gap, said casing being formed with endwise sections detachably connected together, a field coil in the casing surrounding said field magnet, a movable coil disposed in the said air gap, a diaphragm secured to said coil, a support for the rim of the diaphragm, secured to the adjacent end wall of the casing, a spacing ring on the apertured end wall having an opening to exactly fit the adjacent end of the field magnet and bring the two parts of the casing into position where the air gap will be of uniform width throughout, and a shiftable locking connection between the moving coil and the apertured end wall for centering the said coil with relation to the opening in the spacing ring, said spacing ring being provided with a plurality of notches so positioned as to disclose the position of the movable coil relative to the apertured end wall when viewed from within the casing.

4. A loud speaker comprising a casing composed of magnetizable material, having an opening in one end wall, a field magnet within the casing fixed to the opposite end wall and projecting into said opening so as to leave an annular air gap, said casing being formed in endwise, separable sections, and detachably connected together, a field coil removably received in said casing and loosely surrounding the said field magnet, a movable coil disposed in said air gap, a sound-regenerating diaphragm secured to said movable coil, a support for the rim of said diaphragm, secured to the adjacent end wall of the casing, a spacing ring on the apertured end wall of the casing, having an opening to exactly fit the adjacent end of the field magnet and bring the two parts of the casing into position where the air gap is of uniform width throughout, and a unitary shiftable, flexible connection between the movable coil and the apertured end wall,

for centering the said coil with relation to the spacing ring, whereby the coil can be secured to and centered upon said end wall independently of said support for the rim of the diaphragm.

5. A loud speaker comprising a casing formed of magnetizable material having an opening in one end wall, a field magnet within the casing fixed to the opposite end wall and projecting into said opening so as to leave an annular air gap, said casing being formed in endwise, separable sections, detachably connected together, a field coil in the casing surrounding said field magnet, a movable coil disposed in the air gap, a conical diaphragm secured to said coil, a flexible support for the rim of the diaphragm, a second flexible support for retaining the movable coil in a central position with respect to said air gap, and a plate like mounting for said second flexible support movably mounted upon the outer surface of said first end wall independent of the flexible support for the rim of the diaphragm to facilitate a centering of the movable coil to which the diaphragm is attached without moving the diaphragm support.

6. In a loud speaker of the moving coil type the combination of a frame structure having oppositely disposed end portions between which an energizing coil is mounted, a magnetic core for said coil secured to one of said end portions and projected through an opening in the opposite end portion, said opening in said latter end portion being larger than the projecting end of said core to provide an annular air gap, a diaphragm support mounted upon said latter end portion, a conical diaphragm having its periphery secured against radial movement upon said diaphragm support, a diaphragm actuating coil upon said diaphragm disposed around the end of said core and in said air gap, an axially flexible support for said coil, and means upon which said flexible support is mounted, adjustably secured to the adjacent end portion, whereby the diaphragm actuating coil and said flexible support may be adjusted upon said latter end portion to locate the diaphragm actuating coil concentric in the air gap without displacing the diaphragm on its support.

7. In a loud speaker of the moving coil type the combination of a magnetic field frame member having an axially extending portion upon which there is formed an open end portion with an outwardly extending flange and a closed end portion in which there is formed an opening, a second frame portion secured to the outwardly extending flange of said first portion, and a core secured upon said second frame portion adapted to project into the opening in said first portion to form an annular air gap.

8. The method of mounting and centering

the moving coil of a conical diaphragm of the character described having a fixed support at its periphery, which consists in securing a coil supporting element upon a movable plate which may be adjusted and secured upon the outer magnetic pole independently of the fixed support at the periphery of the diaphragm, whereby the coil can be conveniently adjusted and centered in proper relation in the air gap without disturbing the diaphragm support.

9. In a loud speaker of the electro-dynamic type, the combination of a magnetic frame structure having an inner pole and an outer annular pole between which an annular air gap is formed, a diaphragm having an actuating coil adapted to be disposed in said air gap, a supporting means for the periphery of said diaphragm mounted upon and carried by said annular pole piece, and adjustable plate secured upon said annular pole piece independently of said supporting means, and a flexible centering device attached to the diaphragm adjacent its actuating coil and secured to said plate, said plate being adjustable upon said annular pole piece independently of the supporting means for the periphery of the diaphragm so that the coil can be centered within the gap independently of the diaphragm support.

10. In a loud speaker of the electro-dynamic type, the combination of a magnetic frame structure having an inner pole and an outer annular pole between which an annular air gap is formed, a diaphragm having an actuating coil adapted to be disposed in said air gap, a supporting means for the periphery of said diaphragm fixed upon said annular pole piece, an adjustable plate having an outwardly projecting surface secured upon said annular pole piece independently of said supporting means, and a flexible centering device attached to the diaphragm adjacent its actuating coil and secured to the outwardly projecting surface upon said plate, said plate and flexible centering device being adjustable upon said annular pole piece independently of the support for the periphery of the diaphragm so that the coil can be centered within the gap independently of the diaphragm support.

11. In a loud speaker of the electro-dynamic type, the combination of a conical diaphragm having an actuating coil secured thereto, an inner pole piece, an outer pole piece disposed about the end of said inner pole piece and forming an annular air gap for the actuating coil upon said diaphragm, a supporting means secured upon said annular pole piece projecting outwardly therefrom upon which the periphery of said diaphragm is secured, a second support for said diaphragm comprising a plate adjustably secured upon said annular pole piece independently of said first support, and a one piece

flexible member extending from said diaphragm and secured to said plate.

12. In a loud speaker of the electro-dynamic type, the combination of a conical diaphragm having an actuating coil secured thereto, an inner pole piece, an outer pole piece disposed about said inner pole piece to form an annular air gap for the actuating coil upon said diaphragm, a supporting means secured upon said annular pole piece projecting outwardly therefrom upon which the periphery of said diaphragm is supported, a second support for said diaphragm comprising a plate having outwardly projecting portions adjustably secured upon said annular pole piece independently of said first support, and a one piece flexible member extending from said diaphragm and secured to said outwardly projecting portions upon said plate.

EDWIN S. PRIDHAM.
